UNITED STATES PATENT OFFICE.

JAMES M. BRESEE, OF MATTOON, ILLINOIS.

ROAD-MACHINE.

1,128,655.

Specification of Letters Patent. Patented Feb. 16, 1915.

Application filed October 23, 1913. Serial No. 796,900.

To all whom it may concern:

Be it known that I, JAMES M. BRESEE, a citizen of the United States, residing at Mattoon, in the county of Coles and State 5 of Illinois, have invented certain new and useful Improvements in Road-Machines, of which the following is a specification.

This invention relates to improvements in road machines, and has for its object to 10 provide an improved form of road machine of the type shown and described in my co-pending application 764,777.

In a machine of the class described, I find it desirable at times to use another form of 15 means for positively spreading the scraping members and securing them in adjusted relation to the body.

Another object is to provide, in a machine of the class described, having extensible 20 bars, means to maintain in spread relation, said scrapers. Where said bars also provide a fulcrum or derrick for the raising and lowering of said scrapers, I also provide means for reducing the friction thereof and 25 insuring meshing of the gearing, as will be more fully described.

Other objects will be set forth and made apparent in the following specification and accompanying drawings, in which—

30 Figure 1 is a plan view of my improved machine. Fig. 2 is a side elevation of the same. Fig. 3 is a front elevation of the same. Fig. 4 is a detail partially in section of a shaft locking means. Fig. 5 is a plan 35 view of the same showing extensible bars with the racks and pinions. Fig. 6 is a detail of my spreader bar construction. Fig. 7 is a plan view of the same. Fig. 8 is a partial perspective of the same. Fig. 9 is a 40 partial detail view of an extensible bar guiding means. Fig. 10 is a side elevation of the same.

Like numerals refer to like elements throughout the drawings, in which—
45 10 indicates generally the body of my machine having the longitudinal beams 11 rigidly secured together by a cross beam 12 at the front thereof and the structure generally indicated by numeral 13 at the rear 50 portion thereof, this structure being similar in my co-pending application and not requiring an amplified description herein. Scraper bars 14 are located outwardly of the body and pivotally attached adjacent 55 their rear extremities to the cross beam 15 carrying a pulley 16 over which travels the

cable or rope 17 secured at one extremity to an eye-bolt 18 and passing over pulley 19 to the winding drum 20 operable by the hand wheel 21. The cable 17 may be used to 60 raise or lower the rear portion of the scrapers 14 through the medium of the beam 15 as will be apparent.

Uprights 22 extend upwardly from and are secured to the beams 11 and carry the 65 spaced apart bracket arms 22^a at their upper portion journaled in and extending between which are the shafts 23 upon which are carried the winding drums 24 operable by the hand wheels 25 for a purpose to be herein- 70 after described.

A transverse guiding member 26 is located above the body 10 and extends across and is secured to the uprights 22 projecting at either side some distance beyond the body 10, 75 as will be apparent in Fig. 3. This guide member is shown in detail in Fig. 4 and comprises the channel 26^a having the upwardly extending flanges 26^b. At its extremities are located the rollers 27 rotatably 80 mounted in brackets 28 carried at the under side of said beam 26. At its central portion is located the inverted channel section 29 forming a short closed passage as clearly shown in Fig. 5. This is secured to the 85 lower channel 26^a by the side plates 30 and the shaft 31 extends through both said chambers and is journaled therein as clearly shown.

Extensible bars 32 are slidably mounted in 90 the guide member 26, said extensible bars being preferably two in number and spaced apart as shown in the drawings. These bars 32 comprise I-beams in one channel on which are located the racks 33 adapted to cooperate with the pinion 34 mounted on shaft 31. It will be apparent that rotation of the shaft 31 will operate to move the bars 32 in 95 opposite directions.

An upright roller 35 is located adjacent 100 each end of the guide beam 26, being held in place thereon by the arm 35^a and pin 35^b, as shown in Fig. 9. This roller coacts with the flanges 32^b, the same being of sufficient size 105 to prevent contact of the teeth of the corresponding rack 33. This roller 35 is spaced from one flange 26^b of the guide member 26 a sufficient distance to permit sliding of the corresponding bar 32 therebetween, but also so as to insure a fairly snug fit thereof. 110 One of these rollers 35 coacts with each of the extensible bars, the rollers being oppo-

sitely disposed with respect to the longitudinal axis of the guide members 26, as will be apparent. The rollers 27 serve to support the weight of the corresponding bars 32 and thereby decrease the friction between them and the guide member 26.

Two pairs of rollers 40 are mounted upon the axles 41 adjacent the center of the beam 26, as clearly shown in Fig. 4, serving to receive the upward thrust of the extensible bars. It will be apparent that when it is desired to extend or draw in the bars 32 rotation of the hand wheel 31^a carried by shaft 31 will accomplish such purpose.

A ratchet or notched wheel 42 is also mounted upon the shaft 31 above the channel 29 and serves for a locking means as will be described hereinafter. A short arm 43 extends outwardly from one side of the plate 30 and pivotally mounted therein is the detent or latch 44 having its extremity 44^a adapted to fit in notches of the ratchet 42 when in the position shown in Fig. 4.

A rod 45 is pivotally attached at 44^a to the opposite extremity of the detent or latch 44 at one extremity and is pivotally attached at its other extremity 45^a to a foot lever 46 having the flattened foot portion 46^a at one extremity and pivoted at its other extremity at 46^b. It will be apparent that depressions of the lever 46 will release the ratchet 42 and permit the extensible bars to be extended or drawn in with respect to the body of the machine.

Pulleys 48 are mounted at the outer ends of each of the extensible bars 32 and a rope or cable passes thereover from around pulleys 49 carried by the scrapers 14, the cables 47 being secured at one extremity 47^a to the eyes or shackles 50 in the lower side of the extensible bars 32. These cables 47 extend to their respective winding drums 24 operated by hand wheels 25.

In the operation of this device when it is desired to widen the scrapers, the same may be let down into contact with the road and the stress resulting from contact of these scrapers with the road will operate to draw the former apart to the desired position, the extensible bars 32 either being permitted to travel therewith, or the drums 24 being permitted to allow unwinding of the cables 47 or both.

To maintain the scrapers firmly in scraping position when so spread apart, I provide what I term spreader bars 60 curved outwardly and downwardly from the body of the machine and bent backwardly, as indicated at 60^a, being pivotally secured at their outer extremities 60^b by pins 61 or the like to the scraper bars 14. These spreader bars extend upwardly over the beams 11 of the body 10, being straightened along a portion of their length to lie approximately parallel to the plane of the

body. The beams 11 are slotted or grooved as indicated at 11^a in Fig. 6, the slots being of sufficient size to permit play of the bars therein to provide for the raising or lowering of the scraper bars 14.

The spreader bars 60 are provided with the notches or grooves 60^c along their straightening portion and a pivoted latch or detent 62 pivoted at one extremity to the corresponding beams 11 by means of a pin 65 extending through an offset supporting strip 66 on the beam 11 are adapted to drop into the corresponding notches 60^c to lock said bars 60 against movement with respect thereto, as is clearly shown in Figs. 6, 7 and 8. When it is desired to spread the scrapers apart or draw them in the latches or detents 62 are dropped out of engaging position, shown in full lines in Fig. 8, backward until they rest upon the supporting strips 66 whereupon the spreader bars 60 are free to move laterally with respect to the supporting beams 11 so that movement of the extensible bars 32 or action of the rod to spread the scrapers apart will not be offset by the engagement of the latches with the bars 60.

The notches 60^c in the spreader bars 60 have a width greater than the thickness of the latch or detent 62 in order to permit the horizontal angular movement of the scraper bars between the positions shown in full and dotted lines in Fig. 1.

For convenience in operation and construction, I locate the spreader bars 60 adjacent the uprights 21 so that the operating wheels 25 and 31^a, together with the engaging points of the spreaders 60, are located closely adjacent each other so as to enable the operator to reach them without inconvenience.

It will be apparent, while I have shown and described my device with more or less particularity, that I do not wish to be unduly restricted to such showing or description beyond the scope of the appended claims.

What I claim is:—

1. In a device of the class described, a body, scrapers carried by said body, said scrapers being pivoted adjacent their rear extremities, means to adjust said scrapers inwardly or outwardly relative to said body, means independent of said first-named means to secure said scrapers in adjusted position, said means comprising spreader bars attached to said scrapers and extending across said body, said bars being separately adjustable.

2. In a device of the class described, a body, scrapers movable inwardly or outwardly of said body, supporting members mounted to move transversely of said body, means coacting with said supporting members and connected to said scrapers for rais-

- ing and lowering said scrapers, means to extend or draw in said supporting members to swing said scrapers outwardly or inwardly with respect to said body, and independent means to secure said scrapers in the desired position relatively to said body. 5
3. In a device of the class described, a body, comprising longitudinal beams, scrapers carried by said body, said scrapers being pivoted to move inwardly or outwardly of said body, means to adjust said scrapers inwardly or outwardly of said body, said means comprising spreader bars attached to said scrapers, said body beams being slotted, said spreader bars being adapted to slide freely in said slots across said beams, and means to engage said bars when desired to secure the same in adjusted position relative to said beams. 10
- 20 4. In a device of the class described, a body comprising longitudinal beams, scrapers carried by said body, said scrapers being pivoted to move inwardly or outwardly of said body, means to adjust said scrapers inwardly or outwardly of said body, said means comprising spreader bars attached to said scrapers, said body beams being slotted, said spreader bars being adapted to slide freely in said slots across said beams, said bars being notched, and means adjacent said beams engaging the adjacent of said notches to maintain said bars in adjusted position. 25
- 30 5. In a device of the class described, a body comprising longitudinal beams, scrapers carried by said body, said scrapers being pivoted to move inwardly or outwardly of said body, means to adjust said scrapers inwardly or outwardly of said body, said means comprising spreader bars attached to said scrapers, said body beams being slotted, said spreader bars sliding in said slots across said beams, said bars being 35
- 40 notched, and means adjacent said beams engaging the adjacent of said notches to maintain said bars in adjusted position. 45
- notched, and means adjacent said beams engaging the adjacent of said notches to maintain said bars in adjusted position, said last named means comprising dogs or latches pivoted adjacent said beams and adapted to fit in the adjacent of said notches of said bars to maintain the same in adjusted position. 50
6. In a device of the class described, scrapers movable inwardly or outwardly of said body, supporting members mounted to move transversely of said body, flexible means operatively connecting said scrapers to said supporting members, means to extend or draw in said supporting members to swing said scrapers outwardly or inwardly with respect to said body, and means associated with said flexible means to raise or lower said scrapers relatively to said supporting members. 55
7. In a device of the class described, a body, a scraper carried by said body, means movable transversely of said body to raise or lower said scraper and to positively move the same inwardly and outwardly of said body, and independent means movable transversely of said body to secure said 60 scraper in adjusted position. 65
8. In a device of the class described, a body, scrapers carried by said body at each side thereof, means movable transversely of said body to positively move said scrapers to and from said body, means to raise or lower said scrapers independently of each other, and independent means to secure said scrapers in adjusted position. 75

In testimony whereof, I have subscribed 80
my name.

JAMES M. BRESEE.
